UNITED STATES PATENT OFFICE.

FREDERICK TRAUB, OF PHILADELPHIA, PENNSYLVANIA.

ROCKING AND RECLINING CHAIR.

SPECIFICATION forming part of Letters Patent No. 350,329, dated October 5, 1886.

Application filed July 27, 1885. Serial No. 172,715. (No model.)

To all whom it may concern:

Be it known that I, FREDERICK TRAUB, a citizen of the United States, residing in the city and county of Philadelphia, State of Pennsylvania, have invented a new and useful improvement in Rocking and Reclining Chairs, which improvement is fully set forth in the following specification and accompanying drawings, in which—

10 Figure 1 represents a side elevation of a rocking and reclining chair embodying my invention. Fig. 2 represents a longitudinal vertical section thereof. Fig. 3 represents a transverse vertical section in line $x-x$, Fig. 1. Fig. 15 4 represents an enlarged view of the locking mechanism of the back of the chair. Fig. 5 represents a section thereof in line $y-y$, Fig. 4.

Similar letters of reference indicate corresponding parts in the several figures.

20 My invention consists of a combined rocking and reclining chair, as will be hereinafter set forth.

It also consists of a novel and reliable lock for the adjustable back of the chair.

25 Referring to the drawings, A represents the base of the chair, the same having arm-rests B. Fitted between said rests B, and independent thereof, is the seat portion C and lower end of the back D of a chair, the frame of the 30 body having rockers E, which rest on the shoulders F of the base A and move thereon. A catch, G, and springs H are connected with the base and body, a common feature in rocking-chairs, to which, however, I do not limit 35 my invention: The back D is provided with straps J, which are connected with the sides of the frame of the seat C by means of pivots K, whereby the back may be adjusted in vertical positions or raised and lowered.

40 In order to retain the back in adjusted positions, I employ arms L, which at rear are pivoted to the back and in front serrated or toothed so as to interlock with the teeth M of dogs N, the latter being pivoted to the seat-frame and provided with a handle, P, for convenience of operation. Projecting from the dogs N, on the side opposite to the teeth M, are pins P', for the purposes to be hereinafter stated. To the pivots K are secured cranks 45 Q, and to the latter are pivoted arms Q', which

extend along the sides of the seat-frame and are pivoted in front to cranks Q², which are attached to the lifters S for the leg-support T of the chair, said lifters being pivoted to the seat-frame and carrying rollers which ride on cam-shaped pieces T' on the under side of the leg-support. 55

It will be seen that when the back is moved the cranks Q, arms Q', and cranks Q² receive motion therefrom, and thus the leg-support 60 is raised or lowered and adjusted in harmony with the back. Owing to the cam-shaped pieces T' the lifters S operate the leg-support with rapidity, and avoid being made of great length. 65

The foot-rest U is connected with the leg-support by angular straps V, the limbs of each of which are slotted, as V' V², said straps being connected with the leg-support by means of screws W, which enter the slots V'. Projecting from the sides of the leg-supports are pins X, and from the foot-rest pins Y Y'. In the ends of the respective limbs of the straps V are T-shaped slots V³ and serrations V⁴. The pins Y are adapted to engage with the 75 slots V³, and the pins X with the serrations V⁴. The pins Y' enter the slots V². By loosening the screws W the straps may be disengaged from the pins X, and thus moved up or down, as required, to the extent of the slots V', after 80 which the straps are turned toward the pins X and engaged therewith, the screws W then being tightened, the foot-rest thus being adjusted in a direction parallel with the face of the leg-support. 85

In order to set the foot-rest farther out or nearer to the leg-support, said rest is moved until the pins Y coincide with the outer limbs of the slots V³, and thus the rest may be shifted, as desired. The pins Y are then inserted in the proper slot V³, and the rest moved until said pins reach the ends of the head limbs of the slots V³, and thus, owing to said pins Y and the pins Y', the rest is nicely held in adjusted position. 90

To the rear of the base A is pivoted a prop, Z, which is adapted to abut against the frame of the seat A.

It will be seen that the chair is both rocking and reclining. For rocking purposes the 95

arm-rests B afford holds for the hands, so as to conveniently rock the seat and connected parts. In this case the prop Z is lowered or removed from the seat C. For reclining purposes the prop is raised and the seat and connected parts are prevented from being rocked; but the reclining features are preserved, as is evident.

When the back D is to be adjusted, the teeth M of the dogs N are in the proper serration of the arms L, the rearward strain on the back draws the teeth more firmly against the arms L and causes the pins P' to bear down against said arms, and thus each arm is locked on opposite sides by the dogs and its reliable retention in position is assured. To facilitate the releasing of the arm L from the tooth M and pin P', I cast with the dog N a lug or projection, N', which, when the handle P is operated, serves to throw the ratchets on the arm L clear of the teeth M.

Having thus described my invention, what I claim as new, and desire to secure by Letters Patent, is—

1. A combined rocking and reclining chair, consisting of a base with arm-rests and an adjustable back pivotally connected with the seat portion, the said back and seat being independent of the arm-rests, and the said seat having rockers resting on the shoulders of said base, substantially as described.

2. The seat C, having a back adjustably secured thereto, in combination with pivoted levers connected with said back and operating a leg-support attached to the frame of said seat, rockers attached to said seat and resting on an independent frame, the arm L, the dog N, and a foot-rest attached to said leg-support, substantially as described.

3. The frame A and arm-rests B, in combination with seat C, having rockers E resting on said frame, a back pivotally attached to a seat-frame and having a fastening device, substantially as described, a series of levers connected with said back and operating a lifter, a leg-support pivotally attached to the seat-frame and having a cam on its under side, and a foot-rest attached to the leg-support, all of said parts being arranged and combined substantially as and for the purpose set forth.

4. In a combined rocking and reclining chair, the leg-support T, pivoted to the seat and having on its under side the cam T', in combination with the lifter S, connected by cranks Q² Q and arm Q' to the back D, substantially as and for the purpose set forth.

FREDERICK TRAUB.
